BUTTON SEWING MACHINE

Samuel W. Avis, Providence, R. I., assignor to The Reece Button Hole Machine Company, Boston, Mass., a corporation of Maine

Application December 24, 1936, Serial No. 117,550
In Great Britain February 24, 1936

22 Claims. (Cl. 112—110)

This invention relates to machines for sewing on buttons, especially substantially flat buttons having perforations or holes through which the attaching thread is passed. Such buttons are of a wide variety of shapes and sizes, the number and spacing of the thread receiving holes differing in different buttons, and the number of stitches required for their satisfactory attachment varying with the number of holes, the size of the buttons, and the purpose and location of their attachment.

In a prior application, Serial No. 89,330, filed July 7, 1936, by Franklin A. Reece and the present applicant jointly, is described and claimed an improved button sewing machine which can be set to attach either a two-hole or a four-hole button, having holes of any spacing within the range of the machine, by means of a variable number of groups of stitches of a variable number of stitches each, the thread being secured by a tying stitch at the completion of each group of attaching stitches. Said machine is entirely automatic and, having been set in operation with the work properly positioned therein, will perform and complete the sequence of operations for which it has previously been set or adjusted and thereafter come to rest.

The present application relates to certain portions or features of the operating and controlling mechanism of automatic button sewing machines of the type above referred to, which features were the sole invention of the present applicant.

The objects of the invention, together with means whereby the latter may be carried into effect, will best be understood from the following description of an illustrative embodiment thereof shown in the accompanying drawings. The particular mechanism described and shown has, however, been chosen for purposes of exemplification merely, as it will be obvious to those skilled in the art that the invention, as defined by the claims hereunto appended, may be otherwise embodied without departure from the spirit and scope thereof.

In said drawings:

Fig. 1 is a side elevation, partly broken away, of the complete machine.

Figs. 2 and 3 are detail views illustrating the attachment of two different types of buttons.

Fig. 4 is a horizontal section taken substantially on the line 4—4, Fig. 1.

Fig. 5 is a horizontal section taken substantially on the line 5—5, Fig. 1.

Fig. 6 is a front elevation, partly broken away, of the complete machine.

Fig. 7 is a vertical section taken substantially on the line 7—7, Fig. 1.

Fig. 8 is a view similar to Fig. 7 with certain parts broken away.

Fig. 9 is a plan view, and

Fig. 10 a side elevation of the main cam.

Figs. 11 and 12 are sections on the lines 11—11 and 12—12, respectively, Fig. 10.

Fig. 13 is a fragmentary plan view of the mechanism for producing the horizontal or transverse movements of the needle.

Fig. 14 is a detail section taken substantially on the line 14—14, Fig. 13.

Fig. 15 is a detail section taken substantially on the line 15—15, Fig. 14.

Fig. 16 is a detail perspective view of the lower needle bar guide carrier through which the horizontal movements of the needle are effected and controlled.

Fig. 17 is a fragmentary plan view of a part of 20 the looper operating mechanism.

Fig. 18 is a fragmentary detail view, partly broken away, of certain of the parts shown in Fig. 17.

Fig. 19 is a section on the line 19—19, Fig. 18. 25

Fig. 20 is a fragmentary assembly view, in side elevation but partly broken away, of the mechanisms for operating the needle and loopers.

Figs. 21 and 22 are detail sections taken substantially on the lines 21—21 and 22—22, respectively, Fig. 20. 30

Fig. 23 is a detail section taken substantially on the line 23—23, Fig. 22, showing the parts in a different position of adjustment from that shown in Fig. 20. 35

Fig. 24 is a fragmentary longitudinal vertical section, taken substantially on the line 24—24, Fig. 28, of the rear portion of the machine, showing certain of the driving connections.

Figs. 25, 26 and 27 are fragmentary detail views of certain of the parts in Fig. 24, showing them in different positions.

Fig. 28 is a horizontal section taken substantially on the line 28—28, Fig. 24.

Fig. 29 is a detail section taken substantially on the line 29—29, Fig. 24.

Fig. 32 is a fragmentary detail view of certain of the parts in Fig. 31.

Fig. 33 is a detail vertical sectional view of certain of the driving connections shown in Fig. 31. 55

- Figs. 34 and 35 are detail sections taken substantially on the lines 34—34 and 35—35, respectively, Fig. 28.
- Fig. 36 is a plan view, partly broken away, of the base or bed of the machine and certain of the parts carried thereby.
- Fig. 37 is a section taken substantially on the line 37—37, Fig. 36.
- Figs. 38 and 39 are sections taken substantially on the lines 38—38 and 39—39, respectively, Fig. 37.
- Fig. 40 is a detail section, taken substantially on the line 40—40, Fig. 36, and Fig. 40a a detail perspective view of the thread cutter.
- Fig. 41 is a detail fragmentary plan view, partly in section, of portions of the tying-stitch-forming and thread-cutting mechanism.
- Fig. 42 is a detail section taken substantially on the line 42—42, Fig. 41.
- Fig. 43 is a detail section taken substantially on the line 43—43, Fig. 42.
- Fig. 44 is a fragmentary sectional perspective view of a portion of the mechanism shown in Fig. 41.
- Fig. 45 is a detail section taken substantially on the line 45—45, Fig. 44.
- Fig. 46 is a side elevation, Fig. 47 a plan view, and Fig. 48 a front elevation, all partly in section, of the thread take-up, pull-off, and tension mechanism.
- Figs. 49 and 50 are fragmentary perspective views of parts of the same mechanism.
- Fig. 51 is a fragmentary perspective view illustrating the devices for setting the machine in accordance with the number of stitches and stitch groups desired.
- Figs. 52 to 58 are detail views, partly in front elevation and partly in section, illustrating the operation of the stitch-forming mechanism during the tying-stitch-forming cycle.
- Figs. 59, 60, 61 and 62, are diagrammatic sectional perspective views substantially corresponding respectively to Figs. 54, 56, 57 and 58.
- Fig. 63 is a similar view, corresponding substantially to Fig. 59, illustrating a modification.
- The invention is herein illustrated as embodied in a button sewing machine of the general type disclosed and claimed in an application, Serial No. 60,616, filed January 24, 1936, by Franklin A. Reece, wherein all of the movements necessary to attach either a two-hole or a four-hole button are imparted to the stitch-forming instrumentalities as distinguished from the work-holding instrumentalities. In order to make clear the purpose and operation of the mechanism to which the present invention relates, the general construction and operation of the machine of said application will be described.
- Referring to Figs. 1 and 4 to 7, the frame or casing of the machine comprises a base or bed 70 and an overhanging head 71 supported therefrom by an upright housing portion 72 enclosing the principal parts of the operating and controlling devices. For convenience of assembly and repair said frame or casing comprises two separable main sections A' and A2 connected and relatively positioned by dowels a (Figs. 1, 4, 24 and 30) and several attached minor parts all of which collectively afford the necessary enclosures, supports, bearings, etc, for the various moving parts.
- The bed 70 carries a work or throat plate 73 upon which the fabric W to which the buttons are to be attached is supported and against which it is clamped by a presser foot 74 carrying a but-ton clamp 75 for holding the individual buttons and positioning them for the operation of the sewing instrumentalities.
- The main driving and controlling instrumentalities include a main power shaft 76 journalled in suitable bearings in the head 71 and to which power may be applied through a belt pulley 77 under the control of automatic stop mechanism hereinafter described; a vertical cam shaft 78 journalled in suitable bearings in the housing 72, driven through connections hereinafter described from the main shaft 76, and provided with suitable cams for controlling the movements of the several instrumentalities; and a horizontal looper shaft 79 journalled in suitable bearings in the base 70 and operated and controlled from the cam shaft 78.
- The stitch-forming instrumentalities include an eye-pointed needle 80 carried by a needle bar 81 mounted for vertical or longitudinal reciprocation in the head 71 and a pair of loopers 82 and 83 on a looper carrier 84 secured to the looper shaft 79 adjacent its forward end. Except as hereinafter mentioned, these instrumentalities may be substantially as shown and described in the Dahl Patent No. 862,238, August 6, 1907, but, specifically, as shown herein are substantially as more fully shown and described in application Serial No. 64,693, filed February 19, 1936, by Joseph H. Pikul. The sewing thread t is supplied to the needle 80 from a suitable source, not shown, through suitably arranged guides on the head and needle bar and shown, for example, at 86 and 87, under the control of thread handling mechanism hereinafter described.
- The needle bar 81 is longitudinally reciprocated by a crank pin 90 carried by a disk 89 on the shaft 76 and connected by suitable linkage 91 with a collar 92 on said needle bar, and is guided adjacent its upper end in a bearing 93 which, as shown, is pivoted at 94 to a stud 95 swivelled in the head 71. The axes of the pivot 94 and stud 95 are perpendicular to one another, and the construction is such as to permit the needle bar a universal swinging movement about the point of intersection of said axes. Adjacent its lower end the needle bar is guided in a bearing 96 similarly mounted by means of a universal joint 97 on the front end of a carrier member 98 mounted, as hereinafter described, for movement in a horizontal plane both laterally and longitudinally of the machine frame.
- In attaching a two-hole button B, as shown in Fig. 2, the carrier 98 is oscillated laterally between successive descents of the needle 80 to cause said needle to pass alternately through the holes h and hx in the button, the looper carrier being at this time oscillated by the shaft 79 to cause the loopers to cooperate with the needle in the formation of stitches s passing through said holes and serving to attach the button to the fabric W. In attaching a four-hole button, such as shown at B' in Fig. 3, the same operations are performed to form a series of attaching stitches s' passing through the holes h1 and h2, after which the carrier 98 is shifted longitudinally, or in a direction fore and aft of the machine, to bring the needle into the plane of the holes h3 and h4 of the other pair, the looper shaft 79 with the looper carrier 84 and loopers 82 and 83 being similarly shifted to maintain the cooperative relationship of said loopers with the needle. Thereafter the sewing operations are repeated to form a second set of attaching stitches s2 passing through the holes h3 and h4.
- The carrier member 98 for the lower needle 75

bar guide 96 is guided for longitudinal movement in a groove in the top of a head 106 (Figs. 1, 4, 13 and 20) having a shank or trunnion 107 received in a socket 108 in the bottom wall of the head 71 of the machine, whereby said head 106 is pivoted for oscillation about the axis of said shank. Said carrier is, therefore, free to move longitudinally in the head 106 or to oscillate laterally with said head about the pivotal axis of the latter.

The carrier 98 is oscillated laterally about the axis of the pivot 107 to cause the needle to pass alternately through the holes h , h_x (Fig. 2), h' , h_2 (Fig. 3) and h_3 , h_4 , by mechanism most clearly shown in Fig. 13. Said mechanism comprises a link 113 having a pin or stud 114 (see also Fig. 7) a downwardly projecting portion of which is received in a longitudinally disposed way 115 (Fig. 16) in the upper face of the carrier 98, and an upwardly projecting portion of which is received in a way 116 (Fig. 7) in a head 117 having a shank 118 pivoted in a bracket 119 in the head 71. The way 116 permits lateral movement of the stud 114, and consequently lateral oscillation of the carrier, while holding said stud against longitudinal movement in the way 115; while the latter way permits longitudinal movement of the carrier 98 independently of said stud as hereinafter explained. The opposite end of the link 113 is provided with a stud 120 received in an arcuate groove 121 in one arm of a lever 122 (see also Figs. 7, 14 and 20) secured to an upright shaft 123 journaled in a bearing 124 depending from the top of the head 71. At its opposite end the lever 122 carries a pair of pins 125 and 126 (see also Fig. 15) adapted, respectively, for alternative engagement with cam grooves 127 and 128 in the upper face of a main cam 129 fast on the vertical cam shaft 78. In order to avoid confusion, the cam grooves 127 and 128 are only partially indicated in Figs. 4, 13, 17 and 28 but are clearly shown in full in Fig. 9. It will be seen that, when either of the pins 125 or 126 is engaged with its groove 127 or 128, rotation of the cam 129 will cause the lever 122 to swing about the axis of the shaft 123, and that this movement will be transmitted from said lever to the carrier 98 through the link 113.

The amplitude of the lateral vibration thus imparted to the carrier 98 will depend upon the point of engagement of the stud 120 with the groove 121, and in order to permit this to be readily adjusted in accordance with the lateral spacing of the holes in the button, the link 113 is provided with a third stud 130 engaged by a fork 131 (see also Figs. 4 and 7) carried by a slide 132 guided for horizontal movement on the side wall of the head 71 by a stud 133 projecting inwardly from said wall and engaging a slot 134 in the slide and a clamp screw 135 projecting through a slot 136 in the wall and in threaded engagement with said slide. By loosening the clamp screw the slide 132 may be moved longitudinally, and by tightening said clamp screw it may be secured in adjusted position.

As shown in Fig. 15, the pins 125 and 126 are formed with rack portions connected by a pinion 137, whereby when one of said pins is moved into operative position in engagement with its groove in the cam 129, the other of said pins will be lifted out of such position. Accordingly said pins may be rendered alternatively operative to place the lever 122 under the control of the cam groove 127 or 128, and thereby vary the number of stitches in each group s , s' or s_2 , (Figs. 2 and

3), as hereinafter more fully explained. One of the pins, herein the pin 125, is formed with a grooved head 138 engaged by a fork 139 (see also Fig. 8) carried by one arm of a bell crank lever L pivoted at L' within a casing 145 (Fig. 7) secured to the exterior of the head 71, said lever being operable, by means hereinafter described, to render either of the pins 125, 126 operative.

The mechanism for moving the carrier 98 longitudinally is likewise shown in Fig. 13 and comprises a link 146 having at its forward end a stud 147 received in a transverse groove or way 148 in the upper face of the carrier 98 adjacent its rear end. This construction permits the carrier to be swung laterally by the link 113, as above described, independently of the link 146 and stud 147. The stud 147 also pivotally connects the link 146 with an arm 149 (see also Fig. 8) on a vertical rock shaft 150 (see also Fig. 7) journaled in suitable bearings on the interior of the main casing, 20 said connection serving to retain the stud 147 in the groove 148. At its rear end the link 146 carries a stud 151 which engages a groove 152 in an arm 153 secured to a second vertical rock shaft 154. Adjacent its lower end the rock shaft 154 25 has secured thereto an arm 155 having a bifurcated end between the branches of which is pivoted the end of a link 156 having a slot 157 to receive a stud 158 (Fig. 20) depending from a bracket or interior frame member 159 (Figs. 7 30 and 8) within the main casing. The link 156 is, therefore, guided on the stud 158 by engagement of the latter with the slot 157 and is supported by a flange or head 160 on the lower end of the stud. The link 156 has secured thereto a pair 35 of contact or cam-follower blocks 161 embracing between them and cooperating with an edge cam 162 rotatably mounted on the stud 158 and the hub of which is provided with a spur gear 163 meshing with a pinion 164 on the lower end of 40 the main cam shaft 78. The gear 163 and pinion 164 are of such sizes as to constitute two to one gearing between the cam 162 and the cam shaft 78, so that the cam 162 is rotated at one half the speed of the main cam 129. Accordingly, 45 after one complete rotation of the cam 129 to cause the cam groove 127 or 128 thereof to produce a predetermined number of lateral reciprocations of the needle bar to form, for example, the group of stitches s' (Fig. 3), the cam 50 162 will cause the carrier 98 and needle bar to be shifted longitudinally of the machine in one direction, after which a second rotation of the cam 129 will cause the necessary number of lateral reciprocations to form the group of stitches 55 s_2 , whereupon the cam 162 will return the carrier and needle bar to their original longitudinal positions.

The amplitude of the longitudinal or fore and aft movement of the carrier 98 and needle bar 60 81 is determined by the position of the stud 151 in the groove 152 of the arm 153, and, in order that this may be conveniently adjusted in accordance with the fore and aft spacing of the holes h_1 , h_2 and h_3 , h_4 , there is provided a fork 65 165 (Fig. 8) carried by a yoke 166 the arms of which are coaxially pivoted in the bracket 119 and in a boss 167 in the top of the head 71 respectively. The pin 168 which constitutes the upper pivot of the yoke 166 extends through the 70 top wall of the head 71 to the exterior of the latter where it is connected with suitable manual operating or adjusting means generally indicated at 169. The length of the slot 152 is such as to permit adjustment of the pin 168 into a po- 75

sition co-axial with the shaft 154, whereupon there will be no longitudinal movement of the carrier 98, thereby adjusting the machine for operation upon a two-hole button.

5 The looper shaft 79 is slidably mounted at its rear end in a sleeve 179 (see Fig. 17) rotatably mounted in a suitable bearing in the frame member 159. Adjacent the forward end of the sleeve 179 the shaft 79 has secured thereto a 10 collar 180, and the contiguous ends of said sleeve and collar are suitably formed to constitute the complementary elements of a slip coupling or clutch connecting the sleeve and shaft for oscillation in unison while permitting longitudinal 15 movement of the shaft relative to the sleeve. At its rear end the sleeve 179 is formed with a head 181 having a transverse bore 182 (see also Figs. 7 and 8) in which a stud 183 is rotatably and slidably mounted. The stud 183 is provided with 20 a forked head 184 in which is slidably received a stud 185 secured within and projecting longitudinally from the end of an arm 186 secured to one end of a transverse rock shaft 187 (see also Figs. 1 and 20) journaled in a suitable bearing 25 in the frame member 159. By this construction the shaft 187 and sleeve 179, although disposed perpendicular to one another, are connected for oscillation in unison. At its opposite end the rock shaft 187 has secured thereto a bifurcated 30 arm 188 between the bifurcations of which is pivoted at 189 the lower end of a link 190. The upper end of the link 190 is provided with a transverse stud 191 (Fig. 17) the inwardly projecting end of which is received in an arcuate groove 192 in one end of a lever 193 fulcrumed at its opposite 35 end on a stud 194 projecting inwardly from the side wall of the housing 72. Intermediate its ends the lever 193 carries a pair of pins 195 and 196 adapted respectively for alternative engagement with cam grooves 197 and 198 (Figs. 10 and 20) formed in the side or periphery of the main cam 129. The pins 195 and 196, like the pins 125 and 126, are formed with rack portions connected by a pinion 199 (Fig. 19) whereby when one is 40 projected into its cam groove, the other will be withdrawn, and vice versa. One of said pins, herein the pin 196, is formed with a grooved head 200 engaged by a fork 201 (Figs. 7, 8 and 51) carried by the other arm of the bell-crank lever 50 L. The arrangement is such that when the pin 126 is engaged with the groove 128, the pin 196 is engaged with the groove 198; and when the pin 125 is engaged with the groove 127, the pin 195 is engaged with the groove 197. The groove 55 197 corresponds to the groove 127, that is to say, the number and timing of the oscillations of the looper shaft 79 produced by the former correspond to the number and timing of the lateral oscillations of the needle produced by the latter. Similarly the groove 198 corresponds to the 60 groove 128. Accordingly, the oscillations of the loopers are synchronized with the lateral oscillations of the needle, and it is obvious that the amplitude of the former must vary with the amplitude of the latter. The amplitude of oscillation of the looper shaft 79 depends upon the position of the stud 191 in the groove 192 of the lever 193, and in order that this position may be suitably adjusted concurrently with the adjustment of the position of the stud 120 in the groove 65 121 of the lever 122, the slide 132 (Figs. 1, 7 and 8) by which the latter stud is adjusted is provided with a depending flange 202 having a slot 203 to receive the outwardly projecting end of the 70 pin 181. Consequently, when the slide 132 is ad-

justed in accordance with the lateral spacing of the holes in the button, the studs 120 and 191 will be simultaneously adjusted to control both the lateral throw of the needle and the amplitude of vibration of the loopers, thereby maintaining the proper relation between the movements of said parts.

When the needle bar carrier 98 is shifted longitudinally, or in a direction fore and aft of the machine, in sewing a four-hole button, in order to transfer the operation of the needle from the plane of one pair of holes, for example, the holes h' , $h2$, to the plane of another pair, for example, the holes $h3$, $h4$, the looper shaft 79 must be likewise shifted longitudinally to maintain the proper cooperative relationship of the loopers to the needle, and to this end, in the construction shown, the following means are provided, reference being had to Figs. 1, 5, 7, 8, 17 and 20. The vertical rock shaft 150, whose arm 149 is connected with the link 146 by the pin 147, has secured to its lower end a second arm 204 connected by a link 205 with a sleeve 206a on the looper shaft 79 and having a portion 206b recessed to receive and embrace a collar 207 secured to said looper shaft, whereby, when the carrier 98 is shifted longitudinally by the lever 153 acting through the link 146, the shaft 79 will be correspondingly shifted longitudinally. It will be noted that the length of the arm 204 is greater than that of the arm 149 to compensate for the difference in distance, from the pivotal center of the needle bar guide 93, of the shaft 79 and needle bar carrier 98, respectively.

The main cam 129 makes one complete rotation for each group of stitches s , s' or $s2$, and the number of stitches of each group depends upon the shape of the cam grooves 127, 197 and 128, 198. Referring to Fig. 9, the cam groove 128 is formed with three radially offset portions, adapted to produce three complete lateral reciprocations of the needle, in synchronism with the vertical reciprocations thereof, and with a concentric portion 231 during which the needle is caused to make two descents through the same hole in the button in order to form a knot or tying stitch. The groove 198 is correspondingly formed to produce the requisite oscillatory movements of the loopers 82 and 83 to cause them to cooperate alternately with the needle in the formation of the attaching stitches and includes a portion 273 (Fig. 10) so shaped as to cause one of said loopers to cooperate twice in succession with said needle when the latter descends twice through the same hole in the formation of the tying stitch, as hereinafter further explained. Consequently, when the pin 126 is engaged with the groove 128 and the pin 196 with the groove 198, each group of stitches will comprise six attaching stitches and a tying stitch, the whole group requiring eight vertical reciprocations of the needle. Similarly the groove 127 is formed with five radially offset portions, the groove 197 being correspondingly formed, so that when the pins 125 and 195 are engaged with the grooves 127 and 197, each complete rotation of the cam will result in the formation of ten attaching stitches and a tying stitch during twelve vertical reciprocations of the needle.

Since the cam 129 makes one complete rotation for a variable number of vertical reciprocations of the needle bar, that is to say, eight reciprocations when the cam grooves 128 and 198 are operative, and twelve reciprocations when

the grooves 127 and 197 are operative, it is necessary to provide variable speed driving connections between the main shaft 16 and the cam shaft 78 to vary the relative speed of said shafts, 5 so that the number of vertical reciprocations of the needle will be in proper relation to the number of lateral reciprocations thereof during the rotation of the cam 129. To this end, in the construction shown, the following mechanism is 10 provided, reference being had particularly to Figs. 7, 24, 28, 31 and 33.

The main shaft 16 has pinned thereto a worm 25 which meshes with a worm gear 26 loose on the cam shaft 78. The hub of the worm gear 26 15 is suitably formed to constitute one element of a jaw clutch 213, the complementary element of which is formed on a spur gear 214 splined on the cam shaft 78. When said clutch elements are engaged, the worm gear 26 is clutched to the 20 shaft 78 so that the drive to the shaft 78 from the shaft 16 is direct through said worm gear and the worm 25 and is in the ratio of one to eight. In order to drive the cam shaft 78 at a lower speed relative to that of the main shaft 16, the 25 worm gear 26 has secured thereto or formed integrally therewith a spur gear 216 which meshes with a spur gear 217 on a sleeve 218 rotatably mounted on a stud shaft 218a depending from the top of the head 71. At its opposite end 30 the sleeve 218 is provided with a second spur gear 219 with which the gear 214 is meshed when moved downwardly to unclutch the worm gear 26 from the shaft 78. The cam shaft 78 is then driven from the main shaft 16 through the worm 35 25, worm gear 26, gears 216 and 217, sleeve 218, and gears 219 and 214, the several gears being suitably proportioned to cause the cam shaft 78 to be driven from the main shaft 16 at a speed ratio of one to twelve. The gear 214 may be 40 moved downwardly to unclutch the worm gear 26 and mesh said gear 214 with the gear 219, by a fork 341 (Figs. 31 and 51) at the free end of an arm 339 formed on a head 337 which is carried by a slide or plunger 338 guided for vertical 45 movement in the machine head 71. The other arm 340 of the head 337 is connected with that arm of the bell-crank lever L which carries the fork 341, said connection comprising a stud 342 projecting from the lever arm and engaging 50 a slightly elongated slot 343 in the arm 340. When, therefore, said lever L is in the position shown in Figs. 7, 8 and 31 to render the grooves 127 and 197 operative through the pins 125 and 195, the worm gear 26 is unclutched from the 55 cam shaft 78 and the drive from the worm gear 26 to the cam shaft 78 is through the gears 216, 217, 219 and 214, but when said lever L is moved into the position to render the grooves 128 and 198 operative through the pins 126 and 196, the 60 worm gear 26 is clutched to the cam shaft 78, and the drive from the worm gear 26 to cam shaft 78 is direct.

The belt pulley 71 (Fig. 1) is loose on the shaft 16 and is adapted to be clutched thereto by a 65 combined clutch and stop mechanism which as herein shown is similar to those shown and described in the patents to Mello, No. 1,227,643, May 29, 1917, and Reece, No. 1,730,014, October 1, 1929. Referring to Figs. 25, 28, 32, 34 and 35, 70 said mechanism includes a ring 276 carried by the pulley 71 and having a pin 277 which projects through a slot 278 in said pulley and is engaged by a spring 279 located in a recess in said pulley, whereby said ring is permitted a limited yielding 75 angular movement with respect to the pulley, in

order to cushion the shock of starting. The ring 276 has a shoulder 280 adapted to be engaged by a clutch dog 281 pivoted at 286 to a hub 282 keyed to the shaft 16 and normally urged into engagement with said shoulder by a spring 283 5 connecting said dog with an arm 284 fixed to said hub. The dog 281 is formed with a stop arm 285 adapted, when the connected parts are rotated in the direction of the arrows on Figs. 32, 34 and 35 to engage a head 287 yieldingly mounted 10 by means of a spring 288 in the end of a stop arm 289 when the latter is in the position shown in full lines in Fig. 25, thereby disengaging the dog 281 from the shoulder 280 as shown in Fig. 32 and stopping the rotation of the shaft 16, the 15 shock of stopping being cushioned by the spring 288. Recoil of the shaft under the influence of the spring 288 is prevented by a pawl 290 normally urged into a position to be engaged by a shoulder 291 on the hub 282 by means of a spring 20 292. The head 287 is formed with a cam surface 293 which cooperates with a plunger 294 slidably mounted in the frame and engaging the pawl 290. The arrangement of the parts is such that, when the stop arm 289 is in the position shown 25 in broken lines in Fig. 25, the head 287 is out of the path of movement of the arm 285 of the dog 281, permitting the latter, under the influence of the spring 283, to engage the shoulder 280, as shown in Fig. 35, thereby connecting the pulley 30 30 71 and hub 282 for rotation in unison in the direction of the arrows. The cam surface 293 at the same time acts through the plunger 294 to hold the pawl 290 in the inoperative position shown in Fig. 35. When the stop arm 289 is in 35 the position shown in full lines in Fig. 25, the head 287 will be engaged by the stop arm 285 to disconnect the parts and stop the machine, as above described. The cam surface 293 at this time permits the plunger 294 to be forced back 40 by the spring 292, thereby permitting said spring to move the pawl 290 into operative position for engagement by the shoulder 291, as shown in Fig. 32.

The stop arm 289 is secured, as by a set screw 45 307 (Figs. 29 and 32), to a rock shaft 305 journaled in the frame and having secured thereto at the exterior of the casing an arm 306 (Figs. 4, 5, 28 and 29) connected with a suitable treadle (not shown), said arm being preferably provided with a spring pressed positioning plunger 296 50 adapted to engage either one of two recesses or depressions (one of which is shown at 297 in Fig. 29) in the outer wall of the casing, thereby releasably retaining the stop arm 289 in either of the two positions shown in Fig. 25. To start the machine, the treadle is depressed, thereby rocking the shaft 305 in the direction to move the stop arm 289 into the position shown in broken lines 55 in Fig. 25. The machine having been started will 60 continue to operate until automatically stopped. For this purpose the following mechanism is provided:

Secured, as by a set screw 308 (Fig. 32), to the inner end of the rock shaft 305 is an arm 65 298 having a bifurcated end between the bifurcations of which is pivoted a bunter 299 having a bevelled free end 300 adapted, when said bunter is in the elevated position shown in Figs. 25 and 27, to be engaged by a stud 301 (see also Figs. 9 70 to 12), projecting from the under side of the main cam 129 when the latter reaches an angular position corresponding to the completion of the tying stitching. Such engagement of the end 75 300 of the bunter 299 by the stud 301 causes said

bunter to be forced toward the right in Fig. 25, thereby rocking the shaft 305 in a clockwise direction and moving the stop arm 289 into the position shown in full lines in Fig. 25 to disengage the 5 clutch and stop the machine. The stud 301 is preferably notched, as shown at 302 in Fig. 12, so that the slight overthrow of the parts incidental to stopping the machine will bring said notch opposite the end of the bunter 299 in order 10 to permit the machine to be again started by operation of the treadle.

A shaft 265 (Figs. 20, 22, 23 and 41) is journaled in the frame and is provided outside the casing with an operating handle 266 whereby it 15 may be conveniently turned. Said shaft is formed with a flattened end portion 303 (Figs. 25, 26, 27, 32 and 51) adapted, when said shaft is turned into the position shown in Fig. 27 to hold the bunter 299 in its operative position in 20 the path of movement of the stud 301 to stop the machine after one complete rotation of the cam 129 and the consequent completion of one group of attaching and tying stitches, as in sewing a two-hole button B, Fig. 2. When turned into 25 the position shown in Figs. 26, 29 and 32, however, the flattened portion 303 permits the bunter 299 to be drawn by a spring 304 into the inoperative position shown in Fig. 26 out of the path of movement of the stud 301, thereby permitting the 30 continued operation of the machine after one complete rotation of the cam 129, as in sewing two groups of stitches attaching a four-hole button B' (Fig. 3), until raised into its operative position by the following mechanism:

35 Pivoted as at 309 (Figs. 24, 25 and 26), to the frame member 159 (Fig. 24) is a bell crank lever having one arm 310 in engagement with a vertically sliding plunger 311 guided in said frame member and adapted, when raised, to lift the bunter 299 from the inoperative position shown in Fig. 26 into the operative position shown in Fig. 25. The other arm 312 of said bell crank lever engages a cam or eccentric 313 formed on the hub of the gear 163 and cam 162. As above 40 explained, the cam and gear assembly 162, 163, 313 makes one complete rotation to two complete rotations of the cam shaft 78 and main cam 129, and the eccentric 313 is so arranged that at the completion of one rotation of the cam 129 the bell crank 310, 312 and plunger 311 will be 45 in the position shown in Fig. 26, but at the completion of a second rotation of the cam 129 said parts will be in the position shown in Fig. 25, thereby lifting the bunter 299 into operative 50 position and causing the stopping of the machine upon the completion of said second rotation.

It will thus be seen that with the shaft 265 in the position shown in Fig. 27 the machine 55 will be stopped after the completion of one group of attaching and tying stitches of a predetermined number depending upon whether the pins 125 and 195 or the pins 126 and 196, are engaged with their respective cam grooves. When, 60 however, the shaft 265 is in the position shown in Figs. 25 and 26, the machine will be stopped after the completion of two groups of attaching and tying stitches each of a number similarly determined.

65 Referring particularly to Figs. 52 to 62, the loops 82 and 83 are formed with thread engaging shoulders 2 and are secured in fixed position on the looper carrier 84 which also carries a pair of loop spreaders 223 and 224 corresponding respectively to the loops 82 and

83. The loop spreaders 223 and 224 are pivotally mounted in the carrier 84 by means of shanks 225 rotatably mounted in said carrier and are normally held with their ends closely adjacent the ends of the loopers and in substantially the same vertical plane therewith, as shown in Figs. 53, 54, 57, 59 and 61, by means of torsion springs 226 interposed between said carrier and tail portions 230 of said loop spreaders, the positions of said loop spreaders under the influence of 10 said springs being determined by angularly adjustable stops 227. Said loop spreaders are moved out of the latter positions to spread the thread loops by means of a cam plate 228 which, during the attaching-stitch-forming cycle, is held stationary, but which is formed with bevelled edges 229 adapted, as the looper carrier is oscillated, to engage the tail portion 230 of one or the other of the loop spreaders and move the same into loop spreading position as shown in Figs. 20 52, 55, 56, 58, 60 and 62.

The operation of the above mechanism in the formation of the attaching stitches is substantially as more fully described in the Dahl patent and the Plikul application, above referred to. 25 As the needle descends alternately through two holes in a button, and rises, leaving behind it a thread loop, the loopers and their respective coacting loop spreaders, 82, 223 and 83, 224, alternately enter said loops, spread the same, 30 and position them for the passage of the needle therethrough during its successive descents. At the completion of the group of attaching stitches, the needle is caused to descend twice through the same hole in the button, due to the concentric 35 portions 231 of the cam grooves 127 and 128, during which the looper mechanism, together with certain associated parts about to be described, operates in such a manner as to form a tying stitch and sever the thread.

40 Referring to Figs. 37 and 39, the cam plate 228 is secured, as by riveting, to a sleeve 232 mounted to turn on a reduced end portion 233 of the looper shaft 79, while the looper carrier 84 has a hub portion 234 clamped or otherwise 45 secured to said reduced portion. The cam plate 228, while free to turn on the shaft, is held against movement longitudinally thereof, in one direction, by engagement of said cam plate with the looper carrier hub, and in the opposite direction by engagement of the end of the sleeve 232 with a shoulder 236 at the end of the reduced portion 233. Surrounding and rotatable with respect to the sleeve 232 is a sleeve 362 to which is 50 fixed a pawl carrier 237. The sleeve 362 is held against movement longitudinally of the sleeve 232, in one direction by engagement with the cam plate 228, and in the opposite direction by engagement with the hub of a gear segment 364 secured to the sleeve 232. Also secured to the 55 sleeve 362 adjacent the gear segment 364 is a second gear segment 365. The gear segments 364 and 365 mesh with complementary gear segments 366 and 367 on a shaft 249 (see Figs. 5, 36 and 41) journaled in the machine frame, the lengths of the gear segments 365 and 366 with respect to the gear segments 364 and 367 being sufficient to permit the above described longitudinal movement of the looper shaft 79 and the parts carried thereon without corresponding 60 movement of the shaft 249. Adjacent its rear end the shaft 249 has secured thereto a collar 385 (Figs. 41, 44 and 45) having an upstanding stud 386 which is embraced by the forked end 65 387 of a lever 388 having a stem 389 journaled 70 75

in the bracket or frame member 390 in which the rear end of the shaft 249 is journaled. The opposite end of the lever 388 is connected by a link 391 with an arm 392 fixed to an upright shaft 252, likewise journaled in the frame member 390. Secured to the upper end of the shaft 252, as by a pin 253, is a head 254 (see also Figs. 20, 21, 42 and 43) which carries a pair of pins 255 and 256 engageable alternatively and respectively with grooves 257 and 258 (see also Fig. 11) formed in the bottom of the main cam 129. The pins 255 and 256 have rack portions connected by a pinion 259 in a manner substantially similar to the pins 125, 126 and 195, 196, as above described. One of said pins, herein the pin 256, is formed with a grooved head 260 engaged by the forked end of a lever 261 (Figs. 20 and 41) pivoted at 262 to the frame and having its opposite end likewise forked, as shown at 263, to embrace a cam 264 (see also Figs. 7 and 8) on the shaft 265, whereby turning of said shaft will operate the lever 261 to engage either of the pins 255 or 256 with its respective groove 257 or 258. The cam grooves 257 and 258 (Fig. 11) are for the most part concentric but include operative portions 272 so arranged as to be engaged by the pin 255 or 256 when the pin 125 or 126 is in the concentric portion 231 of the groove 127 or 128. The form of the cam groove portions 272 is such as to cause two oscillations of the cam plate 228 and pawl carrier 237 during two stitch-forming cycles in the course of which the needle makes two descents through the same hole in the button, as above explained. The cam grooves 197 and 198 (Fig. 10) are each formed with portions 274 and 275, offset in the same manner as the portions producing the attaching-stitch-forming oscillations of the looper but to a lesser extent and of less angular length. The arrangement is such that the pin 195 or 196 engages the cam groove portions 274 and 275 when the pin 125 or 126 is in the concentric portion 231 of the groove 127 or 128 and when the pin 255 or 256 is in the operative portion 272 of the cam groove 257 or 258.

The throat plate 73 (Figs. 36 to 38) is provided with an opening through which the needle passes, and in order to permit the lateral movements of the needle in passing from one hole to the other of the same pair, as well as the fore-and-aft movements of said needle in passing from one pair of holes to another, without making the opening so large as to impair the work supporting function of the throat plate, means are provided for moving said throat plate horizontally in accordance with at least one of said movements of the needle. As shown, the throat plate is formed in two parts 73a and 73b spaced apart to form a needle opening in the form of a transverse slot 325 of a length corresponding to the maximum lateral movement of the needle and of a width just sufficient to permit the needle to pass. The throat plate sections 73a, 73b are separately secured, as by rivets 326, to a slide 327 and are provided adjacent the slot 325 with ribs 393 fitted in an opening in the slide and having their lower edges flush with the lower face of the latter. The slide 327 is guided for longitudinal movement in a way 328 formed in the top of the base 70 and is connected by a stud 329 with the sleeve 206a. Consequently, when the looper shaft 79 is moved longitudinally to cause the loopers to follow the fore-and-aft movement of the needle, the throat plate with its slot 325 will be correspondingly shifted. The slide 327, way

328 and reduced end portions of the throat plate sections are preferably enclosed by a removable cover plate 330 suitably secured to the top of the base 70.

Rotatably mounted on a headed stud 372 on the underside of the slide 327 adjacent the slot 325 is a cutter 370, said cutter being pressed toward the under surface of said slide by a spring 373 (Fig. 40) interposed between said cutter and the head of said stud. As shown most clearly in Figs. 36, 40a and 41, the cutter 370 is formed with alternating short and long radial arms 374 and 375 respectively, the latter being formed at their ends with cutter or shear blade portions 376 adapted, as said cutter is rotated, to sweep across the slot 325, the arms 374 being of insufficient length to reach said slot. Secured to the underside of the slide 327 is a leaf spring 377 (see particularly Fig. 40) having its free end 378 formed to engage between the arms 374 and 375 and thereby yieldingly position the cutter and prevent overthrow thereof. Pivoted at 379 to the pawl carrier 237 is a pawl 371 whose free end is yieldingly held by a spring 380 in position to engage the arms 374, 375 successively as the pawl carrier 237 is oscillated by the sleeve 362 and connections above described, each of said oscillations being of sufficient amplitude to cause the pawl to turn the cutter through an angle corresponding to the angle between the arms 374 and 375, herein 90°. The operation of the mechanism above described in the formation of the tying stitch is illustrated in Figs. 52 to 62. After the formation of the last loop of the group of attaching stitches, for example, the loop *lx* formed by the descent of the needle through the hole *h2*, the needle again descends through the other hole, for example the hole *h'* shown at the left in Figs. 52 and 53, and through said loop *lx* (while the latter is held by the looper 83 and loop spreader 224, and thereafter rises, leaving behind it a loop *la* as shown in Fig. 54. Simultaneously the looper carrier moves, first toward the right (Fig. 53) to cause the looper 83 and loop spreader 224 to release the loop *lx* and cast the same about the needle, and then, under the influence of the cam groove portion 274 (Fig. 10) toward the left to cause said looper and loop spreader to enter the loop *la*, as shown in Fig. 54. During the latter movement the cam plate 228, under the influence of the operative portion 272 (Fig. 11) of the cam groove 257, also moves toward the left, following the movement of the loop spreader 224, so that there is at this time no loop-spreading actuation of the latter, and its entry into the loop *la* with the looper 83 is facilitated (see also Fig. 59). Thereafter, as the needle continues to rise, said operative cam groove portion 272 causes the cam plate 228 and the loop deflector carrier 237 to be turned toward the right, thereby causing the loop spreader 224 to spread the loop *la*, as shown in Figs. 55 and 60. This oscillation of the cam plate is accompanied by an oscillation of the pawl carrier 237 (Figs. 38 and 39) causing the pawl 371 to turn the cutter 370 through an angle of 90°. During this movement of the cutter, one of its short arms 374 passes the needle opening 325 and clears the loop *la*. The needle thereupon descends again through the same hole *h'* and through the loop *la*, which is held open and in a position to receive it by the looper 83 and loop spreader 224, as shown in Figs. 56 and 60. The looper carrier 84 then moves toward the right, causing the looper 83 and loop spreader 224 to release the loop *la* and

- cast the same about the needle as above described in connection with the loop *la* and as shown in Fig. 53. The needle then rises, leaving behind it a loop *lb* which is entered by the looper 5 83 and loop spreader 224, by reason of movement of the looper carrier toward the left under the influence of the cam groove portion 275, as shown in Figs. 57 and 61, the cam plate 228 again partaking of this movement, as above described in 10 connection with Fig. 54. The cam plate 228 thereupon again moves toward the right, spreading the loop *lb* as shown in Figs. 58 and 62, and the accompanying oscillation of the pawl carrier 237 and pawl 371 turns the cutter 370 through a 15 further angle of 90°, causing one of its long arms to move across the slot 375 and the blade portion 376 thereof to cooperate with the edge of said slot and sever one leg of the loop *lb*, as shown in Fig. 62.
- 20 In order to insure the passage of the needle through a loop, such as the loop *la*, in the formation of the tying stitch, said needle may, if desired, be formed with a bevelled or eccentric point 80b (Fig. 63) so disposed as to tend to deflect said needle outwardly when it descends through the work.
- Referring to Figs. 46 to 50, the thread *t*, in its passage from the source of supply to the guides 86, is engaged by a combined tension and pull-off 30 mechanism and a combined take-up and thread-measuring mechanism, which mechanisms cooperate with the stitch-forming instrumentalities above described in controlling the thread during the stitch forming operations.
- 35 The tension and pull-off mechanism includes an upright lever 394 pivoted at 395 in the machine head and carrying above its pivot two tension devices 396, 397 of conventional form and each comprising a pair of discs pressed toward one 40 another by a spring and between which discs the thread passes. The lower end of the lever 394 is connected by a link 398 with the head 399 of a stud 400 swivelled in the upturned end 401 of an arm 402 fast to the upper end of a short upright shaft 403 journalled in a frame member 404 depending from the top of the machine head 71. Secured to the lower end of the shaft 403 is a two-armed lever, one arm 405 of which is connected by a spring 406 with a fixed part of the 45 machine frame and the other arm 407 of which is formed with a bifurcated end to receive a block 408 swivelled on a stud 409 carried by one arm 410 of a second two-armed lever secured to a second upright shaft 411 likewise journalled in 50 the frame member 404. The other arm 412 of said last-named two-armed lever engages at its end a cam 413 secured to the top of the main cam 129. The end of the arm 412 is held in engagement with the periphery of the cam 413 55 by the spring 406, and the shape of said cam 413 is such that, as the main cam makes a complete rotation during the formation of a group of attaching and tying stitches, as above described, the lever 394 is gradually moved from the position 60 shown in broken lines in Fig. 46 into the position shown in full lines therein, thereby gradually drawing from the supply a length of thread in excess of that required for the stitch forming operations. The parts are shown in Figs. 65 47 and 50, and in full lines in Fig. 46, in the positions assumed thereby at the completion of a group of stitches and the severing of the thread by the cutter 370. Immediately upon the beginning of the next group of stitches, the cam 413 70 75 permits the spring 406 to move the arm 394 into

the position shown in broken lines in Fig. 46, thereby releasing to the needle the excess length of thread which has been gradually drawn from the supply during the formation of the first stitch group, so that the needle, in its first descent 5 in the second stitch-group-forming-cycle is insured an adequate supply of thread for the formation of the first stitch.

The take-up and thread-measuring mechanism includes a three-armed lever pivoted on a 10 pintle 414 mounted in and extending across a casing 415 secured to the top of the head 71, said lever having an upright arm 416 extending through an opening 417 in the top of said casing, a second arm 418 connected by a spring 419 15 with the wall of said casing, and a third arm 420 engaged by the upper end of a plunger 421 slidably mounted in the top of the head 71 and engaging at its lower end a cam 422 on the main power or needle shaft 76. The spring 419 acts to 20 hold plunger 421 in engagement with the periphery of the cam 422, and the shape of the latter is such that during each vertical reciprocation of the needle the arm 416 is swung from the position shown in full lines in Fig. 46 to the position shown in broken lines therein as the needle descends and in the opposite direction as the needle rises. The arm 416 is provided with a series of parallel, laterally projecting studs 423 having perforations 424 through which the thread passes. 25 Adjacent the path of movement of the arm 416 is a fixed arm 425 likewise provided with a series of parallel, laterally projecting studs 426 so arranged that, as the arm 416 is moved into the position shown in Fig. 49 and in full lines 30 in Fig. 46 the studs 423 pass between the studs 426, so that the latter deflect the thread out of the straight line connecting the perforations 424, thereby drawing through the tension mechanism a measured length of thread suitable for the 35 formation of a stitch. In order that the length of thread so measured may be varied in accordance with the size of the button, the spacing of the holes therein, the thickness of the work, and the length of the shank or neck desired, the arm 425 40 is adjustably mounted with respect to the limit of rearward movement of the arm 416 so as to vary the extent of the deflection of the thread. As shown, the arm 425 is pivotally mounted on the pintle 414 and is formed with an extension 427 45 provided with an opening to receive the end of a spring pressed plunger 428. The plunger 428 is mounted in a barrel 429 movable in an arcuate slot 430 in the wall of the casing 415 and carried by a plate 431 likewise pivotally mounted on the 50 pintle 414 but adapted to be secured in adjusted position by a clamp 432 operated by a screw 433 extending through the wall of the casing 415. By withdrawing the plunger 428, the arm 425 can be released and swung out of the way for convenience in threading the studs 423. By releasing the clamp 432 the arm 425 and plate 431 can be swung as a unit about the axis of the pintle 414, thereby varying the position of said arm with 55 respect to the extreme position of the arm 416 shown in full lines in Fig. 46. The measured amount of thread drawn off in each stitch-forming operation can be roughly varied by passing the thread through the perforations 424 of a greater or less number of studs 423, thereby varying 60 the number of deflections caused by the studs 426, and a finer adjustment effected by adjusting the plate 431 as above described.

Mounted on the pintle 414 at the exterior of the casing 415 is an arm 434 having an arcuate 65

slot 435 to receive a clamp screw 436 threaded into the casing wall, whereby said arm may be adjustably fixed in position. The arm 434 is formed with an angular end portion 437 adapted, 5 as the arm 416 is moved into the forward position shown in broken lines in Fig. 46, to engage the thread between the two outermost studs 423 and deflect the same.

In operation, as the needle descends, the arm 10 416 moves forwardly from the position shown in full lines in Fig. 46 toward the position shown in broken lines therein, thereby paying out the thread as required by the descent of the needle. When the needle approaches the lower limit of 15 its movement and has passed through a loop held by a looper and its cooperating loop spreader and then released thereby, the thread is engaged by the end 437 of the arm 434 and deflected, consequently drawing the supply back and thereby 20 withdrawing the loop from the looper and loop spreader, as shown in Fig. 53. As the arm 416 moves rearwardly during the ascent of the needle, the thread is released by the arm 434, thereby 25 insuring an adequate amount of thread for the next succeeding loop to be taken by the looper and loop spreader as shown in Fig. 54. As the needle approaches the upper limit of its movement, the thread between the studs 423 is engaged by the studs 426, thereby deflecting the 30 same and exerting a pull thereon between the tension devices and the work which acts to set the stitch and also to draw through the tension devices a measured length of thread for the next 35 stitch.

The thread handling mechanism, above described for the purpose of making clear the complete construction and operation of the machine, is not claimed herein, being covered by the claims of a divisional application filed June 24, 40 1937, Serial No. 150,138.

Referring particularly to Fig. 51, the shaft 265 has fixed thereon a cam 331 (see also Fig. 23) having a raised portion of approximately 90° in length, which cam cooperates with the bifurcated lower end of a lever 332 pivoted intermediate its 45 ends, at 333, to the machine frame. At its upper end the lever 332 carries a pin which is engaged by the bifurcated lower end of one arm of a bell-crank lever 334 likewise pivoted at 335 to the machine frame. The end of the other arm of the bell crank lever 334 is also bifurcated to engage a pin 336 projecting from the head 337 above described. The shaft 265 is mounted for a limited longitudinal movement in opposition to a spring 314 interposed between the casing wall 50 and a collar 315 on said shaft, said spring normally holding the shaft in the longitudinal position shown. Secured to the shaft 265 immediately adjacent the outer face of the casing wall is a disc 316 (see also Fig. 22), said disc being 55 preferably formed integral with the handle 266 and the whole unit being secured to the shaft by a key 317. The disc 316 is provided about its periphery with a series of index characters and also carries a stud 319 adapted to engage any one 60 of a series of apertures 320 in the casing wall, whereby the angular position of the shaft may be fixed with any of the index characters opposite a fixed index or reference pin 321. By drawing the shaft 265 outwardly a limited distance against 65 the tension of the spring 314, the stud 319 may be disengaged from the aperture 320 with which it is engaged, the shaft turned to bring the desired index character opposite the reference pin 321, and the shaft released to permit the spring 314 to reengage the pin 319 with another aper-

ture 320, thereby locking the shaft in readjusted position. As shown in Fig. 23, the index characters on the disc 316 comprise the numerals "8", "16", "12" and "24" disposed at 90° to one another in the order named, reading in a clockwise direction. 5

By the mechanism above described, the number of groups of stitches and the number of stitches in each group may be determined by a setting of the single operating handle 266. The 10 arrangement is such that when the numeral "8" on the disc 316 is opposite the index pin 321, as shown in Figs. 23 and 51, the pins 126, 196 and 256 are engaged with their respective cam grooves 128, 198 and 258 to form the "eight stitch" (i. e., 15 eight vertical needle reciprocations) group, the clutch 213 is engaged for the direct one-to-eight drive, and the shaft 265 is in the angular position shown in Fig. 27 so as to stop the machine after one rotation of the cam 129 and consequently 20 upon the completion of one "eight stitch" group. When the shaft 265 is turned by the operating handle 266 through an angle of 90° in the counter-clockwise direction to bring the numeral "16" 25 opposite the index pin, the positions of the levers 332, L and 334 and of the head 337, due to the shape of the cam 331, remain unchanged, so that the pins 126, 196 and 256 remain engaged with the cam grooves 128, 198 and 258, and the clutch 213 remains engaged for the one-to-eight 30 drive, but the end portion 303 of the shaft 265 assumes the position shown in Figs. 25 and 26, so that the machine is not stopped until after the completion of two "eight stitch" groups. When the shaft 265 is turned through a further angle 35 of 90° to bring the numeral "12" opposite the index pin, the cam 331, acting through the levers 332 and 334, lowers the head 337 and rocks the bell crank lever L in a counter-clockwise direction, thereby disengaging the clutch 213 and in- 40 termeshing the gears 214 and 219 for the one-to-twelve drive, disengaging the pins 126, 196 and 256 from the cam grooves 128, 198 and 258 and engaging the pins 125, 195 and 255 with the cam grooves 127, 197 and 257 to form a "twelve 45 stitch" group, said shaft again assuming the position shown in Fig. 27 so that the machine is stopped after the completion of one such stitch group. When the numeral "24" is brought opposite the index pin, the setting of the gear 214 50 and of the pins 125, 195 and 255 remains unchanged, but the shaft 265 is turned into the position shown in Figs. 25 and 26, so that the machine is stopped after the completion of two 55 "twelve stitch" groups.

I claim:

1. In a sewing machine, stitch-forming elements and operating mechanism therefor having a cycle of operation to cause said elements to form a group of superimposed stitches, said mechanism including a controlling element having a fixed range of movement during said cycle and said mechanism also having provision for varying the number of stitches in the group formed during said movement. 60

2. In a sewing machine, stitch-forming elements and operating mechanism therefor having a cycle of operation to cause said elements to form a group of superimposed stitches, said mechanism including a rotary controlling element having a fixed angular movement during said cycle and said mechanism also having provision for varying the number of stitches in the group formed during said movement. 70

3. In a sewing machine, stitch-forming ele- 75

- ments and operating mechanism therefor having a cycle of operation to cause said elements to form a group of stitches, said mechanism including a controlling element having a fixed range of movement during said cycle and having a plurality of alternatively operative portions adapted respectively to produce different numbers of stitches in the group formed during said movement.
10. 4. In a sewing machine, stitch-forming elements and operating mechanism therefor having a cycle of operation to cause said elements to form a group of stitches, said mechanism including a rotary controlling element having a fixed angular movement during said cycle and having a plurality of alternatively operative portions adapted respectively to produce different numbers of stitches in the group formed during said movement.
15. 5. In a sewing machine, stitch-forming elements and operating mechanism therefor having a cycle of operation to cause said elements to form a group of stitches, said mechanism including a controlling element having a fixed range of movement during said cycle and having a plurality of alternatively operative portions, and associated means selectively cooperative with the several portions to vary the number of stitches in the group formed during said movement.
20. 6. In a sewing machine, stitch-forming elements and operating mechanism therefor including a cam having a plurality of cam surfaces adapted respectively to produce different numbers of stitches during the same range of movement of the cam and alternatively operative cam followers for said cam surfaces respectively.
25. 7. In a sewing machine, stitch-forming elements and operating mechanism therefor including a cam having a plurality of cam grooves adapted respectively to produce different numbers of stitches during the same range of movement of the cam, a lever, a plurality of pins carried by said lever and adapted to enter said cam grooves respectively, and means for alternatively engaging said pins with their respective cam grooves.
30. 8. In a sewing machine, stitch-forming mechanism including a needle, cooperating looper elements, and operating mechanism including a plurality of alternatively operative actuating devices for the needle and a plurality of alternatively operative actuating devices for the looper elements, the several needle actuating devices corresponding respectively with the several looper actuating devices, and the several pairs of corresponding actuating devices being adapted respectively to automatically produce stitch-forming cycles of a different number of stitches each.
35. 9. In a sewing machine, stitch-forming mechanism including a needle, cooperating looper elements, operating mechanism including a plurality of alternatively operative actuating devices for the needle and a plurality of alternatively operative actuating devices for the looper elements, the several needle actuating devices corresponding respectively with the several looper actuating devices, and the several pairs of corresponding actuating devices being adapted respectively to automatically produce stitch-forming cycles of a different number of stitches each.
40. 10. In a sewing machine, a needle, cooperating looper elements, a shaft having means for actuating said needle, a second shaft having means for actuating said looper elements, said last named means being adapted to produce a variable number of operations of said looper elements during the same angular movement of said second shaft, and means for driving said shafts at a variable relative speed.
45. 11. In a sewing machine, a needle, a shaft having means for reciprocating said needle longitudinally, a second shaft having means for vibrating said needle laterally, said last named means being adapted to produce a variable number of lateral vibrations of said needle during the same angular movement of said second shaft, and means for driving said shafts at a variable relative speed.
50. 12. In a sewing machine, a needle, cooperating looper elements, a shaft having means for reciprocating said needle longitudinally, a second shaft having means for vibrating said needle laterally and means for actuating said looper elements in synchronism with the lateral vibrations of said needle, said two last named means being adapted to produce a variable number of lateral vibrations of said needle and operations of said looper elements during the same angular movement of said second shaft, and means for driving said shafts at a variable relative speed.
55. 13. In a machine for sewing on buttons, stitch-forming mechanism, operating mechanism therefor including a rotary controlling element adapted, during each complete rotation thereof, to cause said stitch-forming mechanism to form a group of stitches of a predetermined number, and means adapted to be operated by said element at the completion of each full rotation thereof to stop said machine, said stopping means being adjustable for operation by said element at the completion of a variable number of rotations thereof to vary the number of groups of stitches formed.
60. 14. In a machine for sewing on buttons, a needle, cooperating looper elements, means for reciprocating said needle longitudinally, a rotary cam having a portion for moving said needle laterally to cause it to pass through different holes in the button and a portion for oscillating said looper elements to cooperate with the needle in the formation of stitches, said cam being adapted, during each complete rotation thereof, to cause said needle and looper elements to form a group of stitches of a predetermined number, stop mechanism, and means adapted to be operated by said cam at the completion of each full rotation thereof to operate said stop mechanism to stop the machine, said last named means being adjustable for operation by said cam at the completion of a variable number of rotations thereof to vary the number of groups of stitches formed.
65. 15. In a machine for sewing on buttons, stitch-forming mechanism, operating mechanism therefor including a controlling element having a cycle of operation to cause said stitch-forming mechanism to form a group of stitches of a predetermined number, means adapted to be operated by said element at the completion of each cycle of operation thereof to stop the machine, means whereby said stopping means may be rendered inoperative to stop the machine at the completion of one cycle of operation, and means for automatically rendering said stopping means operative to stop the machine at the completion of a subsequent cycle.
70. 16. In a machine for sewing on buttons, stitch-

forming mechanism, operating mechanism therefor including a controlling element having a cycle of operation to cause said stitch-forming mechanism to form a group of stitches of a predetermined number, an actuating member movable with said controlling element, stop mechanism having an operating member adapted to be engaged by said actuating member to stop the machine at the completion of a cycle of operation of said controlling element, manually operated means whereby said operating member may be positioned in or out of the path of movement of said actuating member, and means for automatically moving said operating member into said path, when not positioned therein, after the completion of a cycle of operation of said controlling member.

17. In a machine for sewing on buttons, stitch-forming mechanism, operating mechanism therefor including a rotary cam adapted, during each rotation thereof, to cause said stitch-forming mechanism to form a group of stitches of a predetermined number, said cam having a projection, stop mechanism, an operating bunter therefor adapted to be positioned in the path of movement of said projection and when so positioned to be engaged thereby upon the completion of each rotation of said cam, manually operated means for positioning said bunter in or out of said path, and automatic means for moving said bunter into said path, when not positioned therein, after the completion of a rotation of said cam.

18. In a machine for sewing on buttons, a needle, cooperating looper elements, means for reciprocating said needle longitudinally, means for vibrating said needle laterally to cause it to pass through different holes in the button, means for operating said looper elements in synchronism with the movements of the needle, said vibrating means and operating means operating in stitch-forming cycles of a predetermined number of stitches each, and common means for simultaneously adjusting both said last named means to vary the number of stitches in said cycles.

19. In a machine for sewing on buttons, a

needle, cooperating looper elements, a shaft having means for actuating said needle, a second shaft having means for actuating said looper elements, adjustable means to vary the number of operations of said looper elements during the same angular movement of said second shaft, adjustable means for driving said shafts at a variable relative speed, and common means for adjusting said looper actuating means and said variable driving means.

5

15

20

25

30

35

40

20. In a machine for sewing on buttons, a needle, cooperating looper elements, a shaft having means for reciprocating said needle longitudinally, a second shaft having means for vibrating said needle laterally and means for actuating said looper elements in synchronism with the lateral vibrations of the needle, said two last named means being adjustable to vary the number of lateral vibrations of said needle and operations of said looper elements during the same angular movement of said second shaft, adjustable means for driving said shafts at a variable relative speed, and common means for simultaneously adjusting said needle vibrating means, looper actuating means and driving means.

21. In a sewing machine, a needle bar, a shaft and connections for reciprocating said needle bar longitudinally, a second shaft and connections for vibrating said needle bar laterally, gearing connecting said shafts, and means whereby said gearing may be adjusted to vary the relative angularity of said shafts and thereby synchronize the longitudinal and lateral movements of said needle bar.

22. In a sewing machine, a needle shaft, a cam shaft disposed transverse thereto, a worm on said needle shaft, a complementary worm gear on said cam shaft, a bushing in which said needle shaft is journaled, said worm and bushing being connected for axial movement in unison, and means for adjusting said bushing axially to vary the relative angularity of said shafts.

SAMUEL W. AVIS.
